PASSBOOK BANK

John W. Hickey, Long Island City, N. Y.

Application April 20, 1953, Serial No. 24,594

Term of patent 14 years

(Cl. D34—11)

To all whom it may concern:

Be it known that I, John W. Hickey, a citizen of the United States, residing at Long Island City, Queens County, State of New York, have invented a new, original, and ornamental Design for Passbook, Bank, of which the following is a specification, reference being had to the accompanying drawings, forming a part thereof.

The passbook shown herein, is shown in broken lines for illustrative purposes only, and the drawing figures are lined to indicate transparency.

I claim:

The ornamental design for a passbook bank, substantially as shown and described.

JOHN W. HICKEY.
